UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-FEEDING MECHANISM.

Application filed December 13, 1923. Serial No. 680,437.

In machines for cutting sheets of varying lengths from a traveling web where the web feeding and cutting mechanisms are adjustable along the endless sheet feeding carrier 5 toward and away from the rotary sheet taking device which is traveling at a fixed speed, it has been usual to drive the endless sheet feeding carrier at a fixed speed sufficient to take care of the longest sheet cut 10 from the web, which fixed speed is excessive for shorter sheets cut from the web.

The object of this invention is to provide means for coincidently adjusting the speed of the endless sheet feeding carrier with the 15 adjustment of the speed of the web feeding and cutting mechanisms with respect to the fixed speed of the sheet taking device so that different lengths of sheets may be fed to the sheet taking device without distortion. This 20 is particularly desirable where the sheets are cut and fed from a web of light weight and loosely woven material, such for instance as burlap, and also where the lengths of the sheets are varied between wide limits.

25 A practical embodiment of my invention is represented in the accompanying drawings, in which

Fig. 1 represents an elevation looking toward the right side of a web cutting and sheet feeding machine including my improvement.

30 Fig. 2 represents an elevation looking toward the left side of the machine.

Fig. 3 represents a detail horizontal cross section taken in the plane of the line III—III of Fig. 2.

The main frame of the machine is denoted by 1 and the auxiliary frame which carries the means for feeding the web and cutting 40 the sheets therefrom is denoted by 2, which auxiliary frame 2 is adjustable longitudinally along the main frame 1 to different distances from the sheet taking device, to provide for the cutting and feeding of sheets 45 of varying lengths. The sheet taking device is herein shown as a set of grippers 3, carried by the cylinder 4 which is rotated at a fixed speed from the main drive shaft 14, through the gears 51, 52. This cylinder 4 50 may be the impression cylinder of a printing press.

The web feeding mechanism is herein shown as including the web feed roll 5, the web feed drum 6 and its coacting web feed rolls 7. The mechanism for cutting the

sheets from the web is shown as comprising the coacting rotary and stationary cutting members 8 and 9. The cross shaft 10 of the rotary cutting member 8 is driven from the vertically disposed extensible shaft 11 at one side of the machine through the gears 12, 13. This shaft 11 is driven from the main drive shaft 14 through the bevel gears 15, 16, the shaft 11 having a sliding interlocked connection with the gear 15 to permit the longitudinal adjustment of the auxiliary frame 2 along the main frame 1 without disconnecting the geared connection between the main drive shaft 14 and the rotary cutting member cross shaft 10, through the extensible shaft 11.

The cross shaft 17 of the web feed roll 5 is driven from the cross shaft 10 of the rotary cutting member 8 through the train of spur gears 18, 19, 20, 21, 22, 23. The web feed drum 6 is driven from the cross shaft 17 through the spur gears 24, 25.

A horizontally arranged sheet feeding tape carrier 26 is carried by the main frame 1 and is arranged to feed the sheets from the cutting mechanism to the sheet taking grippers 3 of the cylinder 4, the tapes of which carrier pass around pulleys 27 at the inner end of the carrier and around the roll 28, the pulleys 29 and the roll 30 at the outer end of the carrier. This sheet feeding tape carrier 26 is driven from the web feed roll cross shaft 17 which carries the gears 23 and 24 as follows:

A longitudinally disposed extensible shaft 31 is driven from the web feed roll cross shaft 17 by the bevel gears 32, 33, the gear 32 being slidably interlocked with the shaft 31 to permit the longitudinal adjustment of the auxiliary frame 2 along the main frame 1. This extensible shaft 31 is also provided with a bevel gear 34 which meshes with a bevel gear 35 carried by a shaft 36, which shaft carries a spur gear 37 which forms a part of a train of spur gears 37, 38, 39, 40, leading to the gear 41 on the shaft 42 which carries the drive roll 29 of the sheet feeding tape carrier 26.

After the auxiliary frame 2 has been adjusted along the main frame 1 toward or away from the sheet taking gripper 3 of the cylinder 4, to cut a sheet of the desired length, the speeds of the web and the tape carrier are adjusted by a common means so as to keep the speed of the tape carrier just

slightly greater than the speed of the sheet being cut. I have shown this common means as a change gear mechanism in the drive for the web feed roll 5, which change gear mechanism includes the change gears 21, 22, the change gear 21 being mounted on a stationary stud shaft 43 and the change gear 22 being mounted on a stud shaft 44, adjustable along a radially elongated slot 45 in a hanger arm 46 pivoted on the shaft 17, the free end of which arm has a concentric elongated slot 47 through which clamping bolts 48 pass into engagement with a segment 49 on the auxiliary frame 2. The elongated concentric slot 47 provides for the introduction of change gears within a limited range to suit sheets of slightly varying lengths, while the segment 49 is provided with a series of holes 50 so that the hanger arm 46 may be adjusted to different positions to permit the introduction of change gears within a much wider range to suit sheets of greatly varying lengths.

From the above description it will be seen that I have provided a common means whereby the speed of the sheet feeding tape carrier can be accurately adjusted at the same time that the speed of travel of the web is adjusted for sheets of varying lengths, such means being very readily introduced without disturbing the other driving connections.

It is evident that various changes may be resorted to in the form, construction and arrangement of the several parts without departing from the spirit and scope of my invention; hence, I do not wish to be limited to the particular embodiment herein shown and described, but

40 What I claim is:—

1. Mechanism for feeding a web and cutting sheets therefrom, a sheet feeding mechanism, a sheet taking device, a carriage for the web feeding and cutting mechanisms adjustable toward and away from the sheet taking device along the sheet feeding mechanism, and a common means for varying the speed of the web feeding and cutting mechanisms and the sheet feeding mechanism.
2. Mechanisms for feeding a web and cutting sheets therefrom, a sheet feeding mechanism, a sheet taking device, a carriage for the web feeding and cutting mechanisms adjustable toward and away from the sheet taking device along the sheet feeding mechanism, and a common means for varying the speed of the web feeding and cutting mechanisms and the sheet feeding mechanism, said means including a change gear device.
3. Mechanisms for feeding a web and cutting sheets therefrom, a sheet taking device, an endless tape carrier for feeding the sheets to the sheet taking device, a carriage for the web feeding and cutting mechanisms adjustable toward and away from the sheet taking

device along the endless carrier, and a common means for varying the speed of the web feeding and cutting mechanisms and the endless carrier.

4. Mechanisms for feeding a web and cutting sheets therefrom, a sheet taking device, an endless tape carrier for feeding the sheets to the sheet taking device, a carriage for the web feeding and cutting mechanisms adjustable toward and away from the sheet taking device along the endless carrier, and a common means for varying the speed of the web feeding and cutting mechanisms and the endless carrier, said common means including a change gear device.

5. A main frame, an endless sheet feeding tape carrier, an auxiliary frame adjustable on the main frame along the endless carrier, web feeding and cutting mechanisms carried by the auxiliary frame, a drive for the web feeding and cutting mechanisms including a change speed device, and a driving connection between the web feeding mechanism and the endless sheet feeding carrier.

6. A main frame, a drive shaft, and an endless sheet feeding tape carrier, an auxiliary frame adjustable on the main frame along the endless carrier, web feeding and cutting mechanisms carried by the auxiliary frame, a driving connection between the drive shaft and the web cutting mechanism including an extensible and contractible shaft, a driving connection between the web cutting and feeding mechanisms including a change gear device, and a driving connection between the web feeding mechanism and the endless sheet feeding carrier including an extensible and contractible shaft.

7. Web feeding and cutting mechanisms, means for varying the speed thereof to cut sheets of varying lengths from the web, and a sheet feeding mechanism driven by said means, whereby the speed of the sheets being fed is varied according to the length of the sheets.

8. Web feeding and cutting mechanisms, means including a change speed device for varying the speed of the web feeding and cutting mechanisms, to cut sheets of varying lengths, and an endless sheet feeding tape carrier driven from said means whereby the speed of the sheets being fed is varied according to the length of the sheets.

9. A rotary sheet taking device traveling at a fixed speed, web feeding and cutting mechanisms, a sheet feeding mechanism, and means for varying the speed of the said mechanisms with respect to the speed of the sheet taking device for feeding sheets of varying lengths to the sheet taking device.

10. A rotary sheet taking device traveling at a fixed speed, web feeding and cutting mechanisms, a sheet feeding mechanism, and means including a speed gear device for varying the speed of the said mechanisms

with respect to the speed of the sheet taking device for feeding sheets of varying lengths to the sheet taking device.

11. A rotary sheet taking device, web feeding and cutting mechanisms, an endless sheet feeding tape carrier, and means for varying the speed of the web feeding and cutting mechanism and of the endless carrier with respect to the speed of the sheet taking device for feeding sheets of varying lengths to the sheet taking device.

12. A rotary sheet taking device, web feed-

ing and cutting mechanisms, an endless sheet feeding tape carrier, and means including a change speed device for varying the speed of the web feeding and cutting mechanisms and of the endless carrier with respect to the speed of the sheet taking device for feeding sheets of varying lengths to the sheet taking device.

In testimony, that I claim the foregoing as my invention, I have signed my name this 10th day of December, 1923.

HOWARD M. BARBER.
